UNITED STATES PATENT OFFICE.

JOHN W. TAMPLIN AND BENJAMIN F. HOLT, OF HANNA CITY, ILLINOIS.

FELLY-BOILER.

SPECIFICATION forming part of Letters Patent No. 410,467, dated September 3, 1889.

Application filed June 15, 1889. Serial No. 314,352. (No model.)

To all whom it may concern:

Be it known that we, JOHN W. TAMPLIN and BENJAMIN F. HOLT, citizens of the United States, residing at Hanna City, in the county 5 of Peoria and State of Illinois, have invented certain new and useful Improvements in Boilers; and we do hereby declare that the following is a full, clear, and exact description of the same, reference being had to the annexed 10 drawings, making a part of this specification, and to the letters and figures of reference marked thereon.

This invention relates to certain new and useful improvements in boilers designed for 15 use in boiling wheel-fellies; and it has for its object to provide a simple, cheap, and efficient device of this character, in which the fellies may be readily boiled in order to render them hard, and tough, and firm, and to 20 prevent the tire from becoming loose, owing to the shrinkage of the rim.

The invention is clearly illustrated in the accompanying drawings, which, with the letters of reference marked thereon, form a part 25 of this specification, and in which—

Figure 1 is a perspective view of our improved boiler with a portion of a rim of a wheel (indicated in dotted lines) as in the process of being treated. Fig. 2 is a vertical 30 transverse section through the same.

The invention in the present instance resides in the peculiar combinations, and the construction, arrangement, and adaptation of parts, all as more fully hereinafter described, 35 shown in the drawings, and then particularly pointed out in the appended claims.

It is a well-known fact that the ordinary carriage-wheels are very apt to have their tires become loose in a very short time in dry 40 weather, owing to the rims shrinking, or in wet weather the parts swell and thus create trouble. By boiling the rims in hot linseed-oil a sufficient length of time the tendency in the wood to swell and shrink is obviated, 45 and the rims are thus fitted for much longer and better use than when not thus treated.

Referring now to the details of the drawings by letter, A designates our improved boiler, which consists of a lamp-chamber B, 50 supported on suitable legs a, and provided with a suitable door b, hinged at the top by

suitable hinges c. The bottom of the lamp-chamber is provided at its front edge with a suitable upturned flange d, which is of sufficient height to prevent the accidental dropping out of the lamp in case the device should be tipped slightly, and yet will not interfere with the ready insertion and removal of the lamp when necessary.

The door b is provided with a suitable handle by which it may be operated, and near its lower edge said door is provided with a plurality of openings e for the admission of air to aid the burning of the lamp.

The lamp C may be of any preferred form 65 of appropriate size to allow it to be readily inserted in or removed from the lamp-chamber, and may have one, two, or more burners, although in the drawings we have chosen to show two. It is provided at its front side 70 with a ring or handle f by which it may be easily handled.

The rear wall of the lamp-chamber is provided with a plurality of holes g, near the top thereof, as shown, for the admission of air.

The tank or oil receptacle D is mounted upon the lamp-chamber, the bottom of the tank forming the top of the said chamber, as shown in Fig. 2. This tank has inclined ends h extending in opposite directions from 80 the centre, the sides of the tank being formed upon a curve, as shown. The upper edge of the tank may be strengthened when necessary by a suitable rim, as at i.

Secured to the front side of the tank, just 85 above the upper edge of the door to the lamp-chamber, is the guard-plate E, which inclines downward and forward and serves three purposes—first, to protect the hinges of the door; second, to form a stop for the door in its upward movement, and, third, to shed any overflowing oil from the tank away from the door, so that it will not pass into the lamp-chamber and come in contact with the flame from the lamp.

In practice the felly to be boiled is placed in the tank, as shown in dotted lines in Fig. 1, the tank having been previously (or afterwards, as preferred) supplied with a sufficient quantity of linseed-oil. The lamp is then 100 lighted and the oil in the tank caused to boil, the rim remaining in the boiling oil a suffi-

cient length of time to render it firm and tough, the oil filling all of the pores. Old wheels now in use may be readily treated in this manner by simply removing the tires and subjecting the rims to the boiling operation in the tank. The ends of the tank form supports for the rim, as shown.

What we claim as new is—

In a device for the purpose described, the combination, with the lamp-chamber, its hinged door, and the tank above the lamp-chamber, of the guard secured to the wall of the tank above the hinges of the said door,

whereby said guard forms the triple function of protecting the hinges, a stop for the door, 15 and a shield to prevent overflowing oil from entering the lamp-chamber, substantially as shown and described.

In testimony that we claim the above we have hereunto subscribed our names in the 20 presence of two witnesses.

JOHN W. TAMPLIN.
BENJAMIN F. HOLT.
